US00D636916S

(12) **United States Design Patent**
Nelson et al.

(10) **Patent No.:** US D636,916 S
(45) **Date of Patent:** ** Apr. 26, 2011

(54) **ILLUMINATING DEVICE**

(75) Inventors: **David Nelson**, Las Vegas, NV (US);
Wai-Ming Law, Yuen Long (HK)

(73) Assignee: **Sol-Light, LLC**, Las Vegas, NV (US)

(**) Term: **14 Years**

(21) Appl. No.: **29/364,167**

(22) Filed: **Jun. 18, 2010**

(51) LOC (9) Cl. **26-05**

(52) U.S. Cl. **D26/60; D26/62**

(58) **Field of Classification Search** D26/60-66,

D26/37, 38, 40, 43, 44, 46, 51, 47, 52, 104;
362/98, 99, 157, 174, 800, 191, 197, 198,
362/269, 270, 274, 277, 278, 281-283, 287,

(57) **CLAIM**

The ornamental design for an illuminating device, as shown and described.

DESCRIPTION

FIG. 1 is a perspective view of an illuminating device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detailed right side view of the base of the illuminating device in FIG. 5;

FIG. 9 is an enlarged detailed left side view of the base of the illuminating device in FIG. 4;

FIG. 10 is an enlarged detailed front view of the head of the illuminating device of FIG. 2;

FIG. 11 is an enlarged detailed rear view of the head of the illuminating device of FIG. 3; and,

FIG. 12 is an enlarged detailed top perspective view of the base of the illuminating device in FIG. 6.
